UNITED STATES PATENT OFFICE.

CHARLES I. SIMPSON, OF NAMPA, IDAHO.

FILTER.

SPECIFICATION forming part of Letters Patent No. 645,288, dated March 13, 1900.

Application filed November 13, 1899. Serial No. 736,825. (No model.)

To all whom it may concern:

Be it known that I, CHARLES I. SIMPSON, a citizen of the United States, residing at Nampa, in the county of Canyon and State of Idaho, have invented a new and useful Filter, 5 of which the following is a specification.

This invention relates to filters in general, and more particularly to that class known as "portable" filters and which are adapted for 10 attachment to a water-supply and comprise a porous body within a casing and through which the water is forced by the pressure of the main.

The object of this invention is to provide a 15 construction wholly of non-corrosive material in which leakage will be effectively prevented and, furthermore, in which ready access of the water to the exterior of the filtering-body may be had.

20 In the drawings forming a portion of this specification, and in which like reference-numerals indicate corresponding parts in the several views, Figure 1 is an elevation of a filter embodying this invention. Fig. 2 is a 25 vertical central section of the filter with the parts assembled. Fig. 3 is a perspective view of the cap employed upon the porous body.

Referring now to the drawings, the filter 30 consists of a casing 5, which is formed of glass, porcelain, or other similar material and which is cylindrical in general shape and has a hemispherical upper end 6, through which is formed a perforation 7, adapted for connection with a supply-pipe 8, which may be a 35 water-main or which may in turn be adapted for connection with a house-spigot. The lower open end 9 of the casing is provided with threads 10, with which are adapted to engage the threads 11 upon the inner periphery of 40 an adjustable cap 12, of porcelain or other material. This cap consists of a disk having an annular flange upon one face and which flange carries the threads 11. Centrally of the cap 12 is formed a screw-threaded perforation 13, 45 with which is connected an outlet 14, through which the filtered water runs.

Within the casing 5 is placed a similarly-shaped porous filtering-body 15, the hemispherical upper end 16 of which enters the 50 similar end of the casing and upon which is disposed a glass or porcelain cap 17, having

a plurality of radiating protuberances 18, which engage the inner surface of the hemispherical end 6 of the casing and hold the cap and the upper end of the porous body spaced 55 from the upper end of the casing to form an interspace 19, which extends down and around the porous body, said body having a slightly-lesser diameter than that of the interior of the casing. The body 15 has a central bore 60 20, which extends from a point adjacent the upper end thereof through the lower end and adapted to register with the opening 13 and tube 14, and thus to form a continuation 65 thereof.

When the parts are assembled, the cap 17 is disposed upon the porous filtering-body, which is then entered in the casing. A washer 21 is then placed in the cap 12, and the cap is screwed onto the casing, thus clamping the 70 washer firmly between the cap and the lower end of the casing and between the cap and the lower end of the porous body, said porous body having such a length that its lower end will lie flush with the lower end of the 75 casing and the washer having a central opening to register with the opening in the cap. It will thus be seen that the porous body will be held spaced from the inner surface of the casing to permit access of water thereto, the 80 water from the pipe 8 striking upon the cap 17 and being deflected downwardly of the casing, and that the water will pass through the filtering-body and outwardly of the tube 14; also, there being no parts to corrode the 85 elements of the construction may be easily assembled and disassembled for cleaning and repair, thus prolonging the life of the filter.

It will be understood that in practice the specific construction shown may be varied 90 and that other materials than those mentioned and other proportions may be used without departing from the spirit of the invention; also, that the washer 21 between the bottom of the filter-stone and the cap 12 may 95 be of rubber or any other suitable material.

What I claim is—

A filter comprising a casing having an inlet-opening at one end, a hollow porous filtering-body disposed within the casing, a cap 100 upon the body and having projections engaging the end of the casing, a cap in threaded

engagement with the casing and adapted to impinge the filtering-body and clamp it with its cap against the end of the casing, and an outlet-pipe engaged with the cap of the casing and communicating with the interior of the filtering-body.

In testimony that I claim the foregoing as

my own I have hereto affixed my signature in the presence of two witnesses.

CHARLES I. SIMPSON.
